UNITED STATES PATENT OFFICE.

BUTLER AMES, OF LOWELL, MASSACHUSETTS.

SAFETY-RAZOR.

1,305,332.

Specification of Letters Patent. Patented June 3, 1919.

Application filed August 16, 1917. Serial No. 186,501.

To all whom it may concern:

Be it known that I, BUTLER AMES, a citizen of the United States, and resident of Lowell, in the county of Middlesex and 5 State of Massachusetts, have invented new and useful Improvements in Safety-Razors, of which the following is a specification.

This invention relates to guarded cutting devices such as safety razors and it has for 10 its principal object the ready adjustment of the cutting blade and guard relatively to each other whereby either a light or a heavy cut may be taken and whereby an unsymmetrical blade may be uniformly adjusted 15 relatively to the guard. Other objects of the invention are to render adjustable devices of the character disclosed in my prior applications, Sr. No. 163,067, filed April 18, 1917; Sr. No. 173,110, June 6, 1917; Sr. No. 20 173,841, June 9, 1917; and 173,929 June 11, 1917, to provide a safety razor of the double edged type with adjusting means such that one side may be adjusted to take a light cut at the same time that the other side is 25 adjusted to take a heavy cut, to eliminate all screw threads and other means of adjustment which render it difficult to keep a razor or the like in a sanitary condition and to avoid the necessity of flexing the cutting 30 blade to secure an adjustment.

In the accompanying drawings,—

Figure 1 is a side elevation of one embodiment of the invention;

Fig. 2 is an end elevation of the same embodiment;

Fig. 3 is a side elevation of the same embodiment, parts being shown in central vertical section;

Fig. 4 is a side elevation of the same embodiment, the parts being shown in detached position and certain of the parts being shown in central vertical section;

Fig. 5 is an enlarged vertical central longitudinal section of a portion of the device;

Fig. 6 is a plan view of the device with the cap removed, showing the blade by dot and dash lines in central position;

Fig. 7 is a view corresponding to Fig. 6 showing the guard shifted laterally relatively to the blade;

Fig. 8 is a view similar to Figs. 6 and 7 showing the two ends of the guard shifted laterally in opposite directions relatively to the blade;

Fig. 9 is an end elevation of the device 55 when in condition to be placed in a case; and

Fig. 10 is a side elevation of the device in the condition illustrated in Fig. 9.

The particular embodiment of my invention chosen for the purpose of illustration is similar to the embodiments disclosed in my former applications above referred to in that it comprises a U-magnet 1, a guard member 2 mounted on the free ends of the 60 U-magnet, and a cap member 3 surmounting the guard member 2 in such manner as to hold a cutting blade 4 between the cap and the guard. The magnetic handle 1 is preferably formed in the shape of a U-magnet 65 70 as illustrated, inasmuch as this form affords greater efficiency both in producing magnetic attraction as hereinafter described and in serving as a handle for operating the device. 75

The present invention is particularly concerned with adjusting the blade and guard member laterally with respect to each other so that either a fine or heavy cut may be taken, or so that an unsymmetrical blade 80 85 may be brought into parallelism with the edge of the guard member, and I have provided means for adjusting one of the said members, the guard member in the particular embodiment of the invention illus- 90 trated, and the preferred means is construct- 95 ed as follows: Cup-shaped members 6 are arranged to fit over the free ends of the U-shaped magnet and these members are preferably slotted so as to have sufficient 100 resiliency to grip the free ends of the mag- net and thereby hold the cup-shaped mem- bers in position thereon. The cup-shaped members are provided at their upper ends with disk shaped members 7 each of which 105 is eccentric with respect to the axis of the cup-shaped member upon which it is mounted. While the eccentric members 7 may be formed either integrally or separately from the cup-shaped members 6 they are prefer- 110 ably formed separately and then secured to members 6 in some suitable manner. As illustrated in the drawings, particularly in Fig. 5, each cup-shaped member 6 is pro- 115 vided with an upwardly extending collar 8 which fits into an opening in the eccentric member 7 and the outer edge 9 of the ex- 120 tension 8 is spun over the disk 7.

The guard member 2 is provided with an opening to receive the eccentric member 7 and the opening in the guard member is preferably provided with a shoulder 11 fitting into a peripheral recess in the lower portion of the disk 7 under the shoulder 12 of the disk. In this way the parts are held together so that they have no appreciable movement with respect to each other in a vertical direction, the upper face of the cup-shaped member 6 bearing against the lower face of the guard member 2, and the shoulder 12 of the disk engaging the shoulder 11 of the guard member. The upper portion of the disk 7 comprising the shoulder 12 is preferably circular in contour but is made eccentric with respect to the axis of the cup-shaped member 6 as illustrated in Figs. 5 to 8, inclusive. The upper portion of the opening in the guard member 2, namely, the portion above the shoulder 11 in which is disposed the upper portion 12 of the disk, is substantially circular in contour but is somewhat elongated. The particular shape illustrated in the drawings comprises two semi-circular ends joined together by relatively short straight sides, the width of the slot in a direction transverse to the guard member being equal to the diameter of the upper portion 12 of the disk and the length being longer than the width by an amount equal to the length of the straight sides. The lower portion of the opening in the guard member, namely, that portion surrounded by the shoulder 11 of the guard member 2, may be of any suitable contour but it is preferably made circular and of sufficient diameter to permit the guard member to be shifted a slight amount in any direction relative to the axis of the cup-shaped member 6 in adjusting the guard member as hereinafter described.

The cup-shaped members 6 are fitted over the ends of the U-magnet 1 until the ends of the magnet engage the bottoms of the cup-shaped members as illustrated in Fig. 3. The blade 4 is placed in engagement with the cap member 3 with the positioning pins 10 in the cap member fitting through the openings 13 in the blade and the cap member and blade will then be placed in position on the guard member as illustrated in Fig. 3, the pins 10 fitting into the openings 13 in the upper ends of the cup-shaped member 6 and preferably extending into contact with the ends of the U-magnet so as to form a complete magnetic circuit from the U-magnet through the pins 10 and cap member 3, the pins 10 and cap 3 being formed of magnetic material. The magnetic flux flowing through this circuit will then hold the parts tightly in the position shown in Figs. 1, 2 and 3, as described in my former applications. In order to prevent magnetic flux being shunted from the cap member through

the guard member, either the guard member or the cup-shaped members are preferably made of some non-magnetic material such as brass, the cup-shaped members preferably being made of brass.

With the parts in this position the guard member may be adjusted laterally of the device by rotating the cup-shaped members 6 on the ends of the U-magnet, the adjustment being effected by virtue of the eccentric disk 7 swinging about the axes of the cup-shaped members 6 and poles of the magnet. With the eccentric disks 7 directed either toward each other or directly away from each other, they being illustrated in Fig. 6 as being directed away from each other, the guard member extends the same distance in each direction laterally of the central longitudinal plane of the device, as illustrated in Fig. 6. If the blade is entirely symmetrical with respect to the openings 13 formed therein, it will extend equal distances over the teeth of the guard member on each side as illustrated in Figs. 2 and 6. If it is desired to adjust the guard member and blade relatively to each other so that the blade will extend a greater or lesser distance out over the teeth of the guard member thereby to obtain a heavier or lighter cut, the cup-shaped members 6 are rotated so that the enlarged portions of the eccentric disks 7 are swung about the axes of the poles of the magnet so as to extend laterally in the same direction. This will force the guard member laterally, for example upwardly as illustrated in Fig. 7, so that the teeth extend out a greater distance on one side and a lesser distance on the other side. The blade and cap member do not move laterally for the reason that the pins 10 fit into the openings 13 in the cup-shaped members which are collinear with the axes of the poles. It will be obvious that any degree of extension of the teeth of the guard member can be obtained by positioning the disks 7 in the various positions intermediate the extreme positions shown in Figs. 6 and 7. When the blade extends out over the teeth a relatively great distance, a heavy cut may be taken by virtue of the fact that the teeth are curved downwardly as illustrated in Fig. 2. As above stated, the opening in the guard member surrounding the lower smaller portion of the disk is of such diameter as to permit the guard member to be shifted in the manner described.

Frequently the blades of the character herein disclosed are not symmetrical with respect to the openings therein, or stated conversely, the openings are not formed symmetrically in the blades, in which event the blade will extend outwardly over the teeth of the guard member a greater distance at one end than at the other end. In the ordinary types of razor this condition

cannot be corrected. However, with the present invention the guard member may be shifted laterally with respect to the blade at one end without being shifted at the 5 other end, thus shifting the guard member into parallelism with the edge of the blade. Moreover, the guard member may be shifted laterally in one direction at one end and in the other direction at the other end as illustrated in Fig. 8, thereby to correct for an 10 excessive degree of asymmetry in the blade.

In the preferred construction embodying the present invention the cup-shaped members 6 are made integral with the guard 15 member and with this arrangement the guard member, blade and cap member may be bodily separated from the U-magnet and placed in the position shown in Figs. 9 and 10 in which position they occupy a very 20 small space and can be readily carried in a flat elongate container which can be readily carried in a vest pocket or other restricted place.

The magnetic pins 10 which bridge the 25 gaps between the ends of the U-magnet and the cap 3 are considerably smaller in cross-section than the magnet poles, as illustrated in Fig. 3 for example, and this results in a concentration of the flux at the points where 30 it enters the cap. Thus where the magnetic lines of force enter the cap they are confined to relatively small areas and are not permitted to spread out over areas equal to the cross-sectional areas of the magnet 35 poles. This results in that it is more difficult to dislodge the cap from the magnet due, I believe, to the fact that in pulling one edge of the cap away from the guard, thereby tending to rotate the cap about its other 40 edge, the flux is not broken gradually, as it would be if spread over a relatively broad area, but is all broken at the same time. For example, if the flux entered the cap 45 throughout the entire width of the cap and the cap were lifted at one edge only, so as to rotate the cap about its opposite edge bearing on the blade, the magnetic path would not be effectually broken until the cap were lifted at the one side a considerable distance 50 inasmuch as the flux could reach the cap at the opposite side resting on the blade. The same action would take place to a lesser extent if, instead of entering the cap throughout the entire width of the cap, the flux 55 entered the cap through a relatively wide area, as for example, throughout the area of the end of each magnet pole. However, by restricting the flux to a relatively small area at the center of the cap it cannot be 60 broken gradually by lifting one edge of the cap but must all be broken at the same time. Thus, in shaving, where the tendency is to lift one edge of the blade and cap, the blade and cap cannot be so readily dislodged when 65 the flux is confined to the region of the cap.

Moreover, the blade and cap cannot be so easily dislodged by accidental contact with the end of the blade or cap.

While I have described only the preferred embodiment of my invention it is to 70 be understood that the ideas involved may be embodied in other forms than herein illustrated, the principal idea being to provide means for shifting the blade and guard member of a cutting device such as a safety 75 razor laterally with respect to each other and preferably without employing any screw threads or other means which will accumulate dirt and preferably without flexing the blade, it being obvious that in the preferred 80 construction of my device the blade is at all times clamped firmly between the guard member and the cap member throughout its entire extent.

I claim:

1. A safety razor comprising a guard member, a handle, and eccentric means connecting the handle with the guard member, whereby the guard member may be shifted laterally of the handle. 85

2. A safety razor comprising a handle, a guard member, and eccentric means for connecting the guard member with the handle, the eccentric means being rotatively mounted on the handle so as to shift the guard 90 member laterally. 95

3. A safety razor comprising a blade, a guard, a handle, and means for mounting the guard upon the handle, said means being adjustable to shift the guard transversely 100 without shifting the blade.

4. A safety razor comprising a blade, a guard, a handle, and means for mounting the guard upon the handle, said means having an adjustable eccentric transversely to 105 shift the guard and blade relatively to each other.

5. A safety razor comprising a blade, a guard, a handle, and means rotatable on the handle for mounting the guard upon the 110 handle, said means having a concentric portion associated with the blade and an eccentric portion associated with the guard, whereby rotation of said means shifts the guard transversely without shifting the 115 blade.

6. A safety razor comprising a blade, a guard, a handle, and a cap rotatable on the end of the handle for mounting the guard upon the handle, said cap having a concentric portion associated with the blade, and an eccentric portion associated with the guard, whereby rotation of said cap shifts the guard transversely without shifting the 120 blade. 125

7. A safety razor comprising a blade, a guard, a handle, a cap rotatably mounted on the end of the handle for supporting the guard, said cap having a portion extending into an opening in the guard, the outer pe- 130

- riphery of said portion being eccentric, and a pin concentrically associated with said cap, said pin extending through an opening in the blade, whereby rotation of said cap 5 shifts the guard transversely without shifting the blade.
8. A safety razor comprising a double-edged blade, a double guard member adapted to guard the double-edged blade, a handle, 10 and means for shifting the guard transversely of the handle without shifting the blade, whereby the guard may be adjusted to permit a heavy cut to be taken with one side of the blade and a light cut with the 15 other side of the blade.
9. A safety razor comprising a double-edged blade, a double guard member adapted to guard the double-edged blade, a handle, and adjustable means connecting the 20 handle with the guard whereby to shift the guard transversely of the handle without shifting the blade.
10. A safety razor comprising a blade, a guard, a handle, a cap rotatably mounted on 25 the end of the handle for supporting the guard, said cap having an annular portion extending into an opening in the guard, the outer periphery of said portion being eccentric and the inner periphery being concentric 30 with the handle, and a pin in the concentric opening of said annular portion extending into an opening in the blade, whereby rotation of said cap shifts the guard transversely without shifting the blade.
- 35 11. A safety razor comprising a guard, a handle, and a cap fitting over the end of the handle with a portion thereof extending into an opening in the guard, said portion having an outer flange overhanging a portion of the 40 guard around said opening.
12. A safety razor comprising a guard, a handle, a member rotatably mounted on the end of the handle for connecting the guard to the handle, said member having a projection 45 extending into an opening of the guard, said projection having an annular recess to receive a portion of the guard surrounding said opening and said projection being eccentric to shift the guard transversely when 50 said member is rotated.
13. A safety razor comprising a guard, a handle, a member rotatably mounted on the end of the handle for connecting the guard to the handle, said member having a projection 55 extending into an opening in the guard, said projection and said opening having outer and inner portions of different diameter, the outer portion of the projection having a greater diameter than the inner
- portion of the opening, and one of said portions of the projection being eccentric to shift the guard transversely when said member is rotated. 60
14. A safety razor comprising a blade, a guard, a handle having spaced portions arranged to support the guard in regions spaced apart along the length of the guard, and means associated with each of said portions of the handle for transversely shifting the guard and blade relatively to each other, 70 whereby the guard may be alined with the blade. 65
15. A safety razor comprising a blade, a guard, a handle having spaced portions arranged to support the guard in regions 75 spaced apart along the length of the guard, and means associated with each of said portions of the handle for transversely shifting the guard without shifting the blade, whereby the guard may be alined with the blade. 80
16. A safety razor comprising a guard, magnetic means disposed on opposite sides of the guard to hold the blade on the guard by magnetic attraction, and means of relatively small width forming a magnetic path 85 between said magnetic means on opposite sides of the guard. 85
17. A safety razor comprising a guard, a magnet on one side of the guard having spaced poles, a cap on the other side of the 90 guard forming a magnetic path between the regions of said poles, and pins of relatively small cross-sectional area extending through the blade and guard in said regions, the pins forming magnetic bridges between said poles 95 and said cap.
18. A safety razor comprising a guard, a magnet on one side of the guard having spaced poles, a cap on the other side of the 100 guard forming a magnetic path between the regions of said poles, and positioning pins projecting from the cap through the guard to said poles.
19. A safety razor comprising a guard, a magnet on one side of the guard having 105 spaced poles, a cap on the other side of the guard forming a magnetic path between the regions of said poles, and positioning pins projecting from the cap through the guard to said poles, said pins being formed of magnetic material and being relatively small in cross-sectional area so as to form a restricted path between said poles and cap for the magnetic flux. 110
- Signed by me at Boston, Mass., this 13th 115 day of August, 1917.

BUTLER AMES.
